[57] **CLAIM**

The ornamental design for an ice cream cone and beverage carrier, as shown and described.

DESCRIPTION

FIG. 1 is a top plan view of an ice cream cone and beverage carrier showing our design;
FIG. 2 is a side elevational view thereof, the other three side elevational views being identical thereof;
FIG. 3 is a bottom plan view thereof; and,
FIG. 4 is a cross-sectional view taken along line 4—4 of FIG. 1.

*Fig. 1.**Fig. 4.**Fig. 2.**Fig. 3.*
